UNITED STATES PATENT OFFICE.

HENRY SCHMIDT, OF DETROIT, MICHIGAN.

DOOR CLOSER.

Application filed August 6, 1926. Serial No. 127,555.

This invention relates to closing devices for doors, and has for its primary object to provide a door closure construction that may be readily installed and that will effectively cause the door to move to fully closed position when pressure upon the same is released.

A further object of the invention resides in the provision of a door closure of the spring type wherein the tension of the spring may be regularly regulated without requiring the detachment of the device, and without requiring any skill whatever, the nature of the spring tension adjusting means being such as to positively prevent the same from slipping, which is the usual case when relying upon nuts, bolts, and the like.

A still further and important object is to provide a closure of the before mentioned type that is so constructed as to permit the ready disassembling of the same for cleaning, repair, or renewal purposes.

Other objects will become apparent as the nature of the invention is better understood, the same comprising the novel form, combination, and arrangement of parts hereinafter more fully described, shown in the accompanying drawing and claimed.

In the drawing wherein like numerals indicate like parts:

Figure 1 is a fragmentary front elevation of a door equipped with my improved closure.

Figure 2 is a longitudinal section through the closure as applied, and

Figure 3 is a perspective of the spring tension adjusting sleeve of the device.

Now having particular reference to the drawing, 5 indicates a hinged door mounted within the usual frame 6. The closure device constitutes the provision of a relatively elongated cylinder 7 mounted horizontally at the upper end of the door 5 and provided at one end with a removable slip type cap 8 that may be secured thereon in any desirable manner, preferably through the medium of screws 9. Arranged within the opposite open end of said cylinder 7 is a plug 10 that is formed at its end outwardly of the cylinder with a circular head 11 through which is a vertical bore 12. Rectilinearly movable within the cylinder is a piston 13 formed with a longitudinal threaded opening for receiving the inner screw threaded end of an elongated piston rod 14 that projects outwardly through an opening in said

cap 8, the outer end of this rod being provided with a flattened head 15, Figures 1 and 2.

Slidably arranged upon the rod 14 toward the cap end of the cylinder 7 is a flanged sleeve 16, the flange of which is formed at its periphery with a threaded opening 17. At this end of the cylinder 7, the same is longitudinally slotted as at 18 and at the lower edge of this slot are spaced notches 19. Extending through the slot 18 and threaded within the flange of the sleeve is a thumb screw 20, and obviously by engaging the screw within the various predeterminedly spaced notches 17, the sleeve 16 will be maintained in predetermined position within the cylinder 7, with the end in view of adjusting the tension of an expansible coil spring 21 that surrounds the piston rod 14 between the piston 13 and said flanged sleeve 16, Figure 2.

Secured to the door 5 at its upper end and at its outer edge is a plated arm 22 secured to the door in predetermined spaced relation with respect to the capped end of the cylinder 7. The outer end of this arm is bifurcated as disclosed in Figure 1 for receiving the flattened end 15 of the piston rod 14 after which said flattened end of the rod is pivotally secured within the bifurcated end of the arm as at 23.

Depending from the upper bar of the door frame 6 adjacent the hinged edge of the door 5 is a bolt 24 that is arranged through the bore 12 in the head 11 of the cylinder closure plug 10, after which said bolt is secured within the bore by reason of a nut 25, this securing means affording a pivotal connection between the cylinder and the door frame.

It will be obvious that when the door 5 is moved to open position, the cylinder 7 will swing in the direction of the movement of the door. At the same time the rod 14 will be pulled away from the cylinder for causing the spring 21 to compress therein.

Obviously upon the releasing of the door, the spring will exert its force to draw the door to closed position.

It will be seen that I have provided a highly novel, simple, and efficient form of closure for doors that is well adapted for all the purposes heretofore designated, and even though I have herein shown and described the invention as consisting of certain detail structural elements it is never-

2
theless to be understood that some changes may be made therein without effecting the spirit and scope of the appended claims.

Having thus described the invention, what 5 I claim as new and desire to secure by Letters Patent is:—

1. In a door closure of the character described, a relatively elongated cylinder, a pivotal connection between one end of the 10 cylinder and the door frame, a piston rectilinearly slideable within the cylinder and attached at one end to a piston rod extending outwardly through the unpivoted end of said cylinder, an abutment slidably arranged 15 upon the piston rod within the cylinder, spring tension means between the piston and said abutment, complementary construction between the abutment and the cylinder whereby the same may be secured in predetermined adjusted relation with respect to 20 the cylinder, and a pivotal connection between the outer end of the piston rod and the door.
2. In a closure for doors, a cylinder pivoted at one end to the door frame, a piston 25

slidable within the cylinder and attached to the inner end of a piston rod arranged within the cylinder, the opposite end of which projects therefrom, a pivotal connection between the projecting end of the piston rod 30 and the door, a sleeve slidably arranged upon the piston rod within the cylinder, complementary construction between the sleeve and the cylinder whereby the sleeve may be secured to the cylinder in predetermined longitudinally adjusted positions, an expandible coil spring surrounding the piston rod between the piston and said sleeve, said complementary construction between the sleeve and cylinder consisting of a lateral screw carried by the sleeve and slideable within a longitudinal slot in the adjacent end of the cylinder, said slot being provided at one of its longitudinal edges with spaced notches for receiving said screw when the 35 same is forced in a direction toward said notches.

In testimony whereof I affix my signature.

HENRY SCHMIDT.
